AUTOMOBILE

Frederick Wagner, Romeo, Mich., assignor to Studebaker-Packard Corporation, Detroit, Mich., a corporation of Michigan

Application April 21, 1955, Serial No. 35,613

Term of patent 3½ years

(Cl. D14—6)

FIG. 1

FIG. 5

FIG. 2

FIG. 3

FIG. 4

FIG. 6

Figure 1 is a fragmentary right perspective of an automobile embodying my new design;

Figure 2 is an enlarged elevational view of the air scoop grille;

Figures 3 and 4 are enlarged sectional views taken along lines 3—3 and 4—4 respectively shown in Figure 2;

Figure 5 is an enlarged view taken on line 5—5 of Figure 1; and

Figure 6 is a front elevational view of the automobile embodying my new design.

The dominant features of my design reside in the full line portion of the drawing. The rear of the automobile is of conventional configuration.

I claim:

The ornamental design for an automobile, as shown and described
